Inventor.
Thomas McKEE,
by Chas. J. Williamson, Attorney.

UNITED STATES PATENT OFFICE.

THOMAS MCKEE, OF PORTLAND, OREGON.

PIANO PLAYER.

Application filed December 10, 1908, Serial No. 466,788. Renewed June 27, 1921. Serial No. 480,720½.

To all whom it may concern:

Be it known that I, THOMAS MCKEE, a citizen of Great Britain, residing at Portland, in the county of Multnomah and in the State of Oregon, have invented a certain new and useful Improvement in Piano Players, and do hereby declare that the following is a full, clear, and exact description thereof.

My invention relates more particularly to automatic piano players, in which perforated sheets are used, and having reference to this particular case, my object, generally stated, is to enable the performer to have before him the music as ordinarily written with all the marks of expression, and in case of vocal music, the words as well, so that the performer may render the particular piece according to the ordinary marks of expression written by the composer thereon, and in the case of vocal music the words be read and sung to better advantage, and apart from this particular purpose, my object is to render more convenient the support or holding of music for piano playing, and to avoid the necessity of turning of leaves. Besides the objects as stated, and the advantages resulting therefrom, my invention secures certain other advantages as will hereinafter be pointed out, and for the accomplishment of the objects and the attainment of the advantages in question, my invention consists in the apparatus and the music therefor, having the characteristics substantially as hereinafter specified and claimed.

Referring to the drawings,

Fig. 1 is a front elevation of a portion of a piano player embodying my invention.

Fig. 2 a vertical section on the line 2—2 of Fig. 1.

Fig. 3 a view similar to Fig. 1, with the doors removed and a portion of the casing broken away.

Fig. 4 a detail view on a larger scale than the other figures, of the lower end of the driving roller for the sheet of perforated paper; and

Fig. 5 a similar view of the idler roller for the perforated paper.

The piano player 10 shown in the drawings in which my invention is embodied, is of ordinary construction, and therefore need not be described, and I consider it necessary only to show a portion of the case and of the keyboard. In the front of the piano case and above the keyboard, I provide an open-

ing 11 through which is passed a box or casing 12, comprising a back wall, end walls, top and bottom walls, and a pair of doors 13, that are pivoted or hinged at their side edges 60 and meet at the transverse center of the piano, and each door at its lower inner corner is cut away, as best shown in Fig. 1, so that when the two doors are closed, the openings thus provided, together with a 65 strip at the bottom of the box or casing 12, will form an oblong display opening 14 to expose or exhibit music 15 written in the usual manner upon staves, together with the words of a song if the music is vocal, the 70 staves running horizontally and the same being printed upon a sheet 16, or the like, of considerable length, which is supported by two vertical rollers 17 and 18, respectively, that are journaled in the box or casing 12, 75 the sheet being wound upon one and unwound from the other to cause the sheet to travel from right to left when the instrument is being played, and from left to right when the performance is ended and it is desired to restore the sheet to the roller upon 80 which it was originally wound, preparatory to another rendition. The movement of the sheet from left to right is preferably faster than in the opposite direction, and to secure 85 the desired rotation of the two rollers, the upper end of the shaft of the slower rotating roller is provided with a bevel gear 19 with which meshes a pinion 20 on a horizontal shaft 21 journaled in bearings above the 90 box or casing 11, and on the upper end of the shaft of the other roller is a bevel pinion 22 with which meshes a gear wheel 23 on said shaft 21, the shaft being longitudinally movable so that but one of the rollers 95 at a time will be in mesh with its bevel gear or pinion, as the case may be, and to disengage both bevel gear and bevel pinion from both rollers, when neither is to be rotated, and to conveniently move the shaft 100 longitudinally for these purposes, it has at one end a grooved collar 24 which is engaged by one arm of a bell crank lever 25, whose other arm is connected by a rod or link 26 to an operating handle 27 conveniently situated at the front of the piano close to the keyboard. The shaft 21 has on it near its other end a sprocket wheel 28 which is splined thereto, from which a sprocket chain 29 runs to a suitable connection with the 110 usual motor.

Although both rollers 17 and 18, at one

time or another, are driven, I prefer to term the roller 17 the driving roller, because it is the one that is positively rotated to move the sheet in the operation of playing the instrument, and said roller 17 has at its upper end a fixed flange 30, and at its lower end an adjustable flange 31 that has a conical externally-threaded and radially-split hub on which is a clamping nut 32, to enable the flange 31 to be clamped at the desired point up and down the roller. The roller flange 31 is vertically adjustable to suit sheets of different widths, according to the number of bars of music, the use of words alone without music, or the use of perforations alone. The music-carrying roller 18 has flanges at its upper and lower ends, and at its lower end has a short shaft 33 which is journaled in a socket in the upper end of a stud or pin 34 that rests at its lower end upon a coil spring 35 in a box 36, this mode of journaling the music roller 18 at its lower end being employed to permit the placing in and removal of the same. At its upper end, the music roller 18 has a short shaft 37 which enters a socket in the pinion shaft 21. The continuous or long sheet 16 besides having the musical characters of ordinary form written or printed upon it, also is or constitutes the customary perforated sheet, and the perforations are made above the written music 15 so that the perforations are concealed when the doors 13 are closed, nothing being visible in the use of the instrument except the music written in the ordinary form on the lower part of the sheet.

In order to enable the music 15 to be placed at the slight angle that is desirable in piano playing, the box or casing 12 is pivoted so that it may be swung from the vertical position shown in full lines in Fig. 2 to the inclined position indicated by dotted lines in said figure, and a convenient manner of so pivoting the box or casing is to suspend it from the shaft 21 by arms or brackets 38 at the top of the box or casing 11. The usual tracker bar 39 over which the perforations pass is secured in the box or casing 11, and to permit of the usual pneumatic connection with said tracker board, notwithstanding the shifting or swinging of the box or casing, flexible tubing 40 is used for making the connection with the tracker board. The usual time indicator 41 is shown in the drawings. The sheet has printed thereon numerals to indicate speed, the numeral 50, for example, for this purpose appearing at the left of the music in Fig. 1 of the drawings.

It will be seen that by means of my invention familiarity with music and the expression marks as commonly written is all that is necessary to enable the accurate interpretation and rendition of a piece of

music, and to one familiar with this, it can be done more satisfactorily than with the expression marks used on perforated music, especially since in the case of my invention the expression marks are associated with the ordinary form of musical rotation; and in the case of vocal music, the words are immediately before the performer, so that they can be very easily and conveniently read. Should it be desired to render the music by playing in the ordinary manner upon the key board, it is necessary merely to disconnect the suction apparatus with the motor, so that the music alone will be caused to pass before the player, and in this connection it will be seen that my invention has the very important advantage of making it unnecessary to turn any leaves because the music is moved continuously and automatically before the performer. It will be evident that my invention may be embodied in an arrangement in which the perforations shall be formed in one sheet and the ordinary musical notation written or printed on a separate sheet, and my invention extends to the writing or printing of music in the ordinary form of notation in a long or continuous sheet, so that it may be caused to pass before the performer. While I have mentioned pianos in particular, it is to be understood that I do not limit myself to the use of my invention with any particular form of musical instrument.

Having thus described my invention, what I claim is—

1. The combination of a key-actuated musical instrument, a sheet perforated for the automatic operation of said instrument and having music thereon in ordinary musical notation including the customary staff or staves, the perforated portions of the sheet being to one side of said staff or staves whereby the characters of the music in ordinary notation are unaffected by the perforations, and a pair of vertical rollers supporting the sheet above the keyboard of the instrument, the front of the piano having a display opening only for the music in the ordinary form of notation.

2. The combination of a key-actuated musical instrument, a sheet perforated for the automatic operation of said instrument and having music thereon in ordinary musical notation, a pair of vertical rollers supporting the sheet above the keyboard of the instrument, and doors having cut away portions to expose only that portion of the sheet which has the ordinary form of musical notation.

3. The combination of a key-actuated musical instrument, a sheet perforated for the automatic operation of said instrument and having music thereon in ordinary musical notation including the customary staff or staves, the perforated portions of the sheet

being to one side of said staff or staves whereby the characters of the music in ordinary notation are unaffected by the perforations, a pair of vertical rollers supporting the sheet above the keyboard of the instrument, and means for pivotally mounting said parts whereby the sheet may be moved into and from an inclined position.

4. The combination of a key-actuated musical instrument, a sheet perforated for the automatic operation of said instrument and having music thereon in ordinary musical notation including the customary staff or staves, the perforated portions of the sheet being to one side of said staff or staves whereby the characters of the music in ordinary notation are unaffected by the perforations, a pair of vertical rollers supporting the sheet above the keyboard of the instrument, means for pivotally mounting said parts whereby the sheet may be moved into and from an inclined position, a tracker board movable with the sheet, and flexible tubing leading from the tracker board.

5. In an automatic musical instrument adapted to play a music sheet having note perforations in the body thereof and indicia pertaining to such note perforations, the combination of means for operatively supporting said music sheet to travel endwise in a direction from one side toward the other side of the instrument while said sheet lies in a sufficiently inclined position relatively to the front of the instrument to enable the performer to visually relate the note perforations in the body of the music sheet with the indicia pertaining thereto, and automatic playing means to cooperate with the music sheet to play it.

6. In an automatic musical instrument, the combination of a music sheet having note perforations and indicia arranged in alinement transversely with the note perforations to which they relate, means inclined forwardly and downwardly relatively to the front of the instrument for operatively supporting the music sheet to travel endwise in a horizontal direction with the music sheet lying in a substantially inclined position before the performer, and automatic playing means to cooperate with the music sheet to play it.

7. In an automatic musical instrument adapted to play a music sheet having note perforations in the body thereof and related indicia upon a margin of the sheet, means inclined substantially in a direction forwardly and downwardly relatively to the front of the instrument for operatively supporting the music sheet to travel endwise in a direction from one side toward the other side of the instrument while the music sheet lies in a correspondingly inclined position to enable the performer more easily to visually relate the note perforations to the

corresponding indicia located on the forward lower margin of the music sheet.

8. In an automatic musical instrument, a tracker-bar substantially inclined downwardly and forwardly relatively to the front of the instrument, a music sheet having note perforations in the body thereof, and related indicia upon the lower margin of the music sheet which is nearest to the performer, and means for operatively supporting said music sheet to travel longitudinally and horizontally across said inclined tracker-bar while the music sheet is substantially inclined in a direction transversely of its length with the indicia thereon located at the forward lower margin of the sheet music.

9. In an automatic musical instrument, a tracker-bar substantially inclined downwardly and forwardly relatively to the front of the instrument so that its lower end will be nearest to the performer, a music sheet having note perforations in the body thereof and indicia upon one of its margins, said indicia being in transverse alinement with and relating to note perforations in the body of the sheet, and spools having their axes inclined to conform substantially with the inclination of the tracker-bar and operative to support the music sheet and to cause it to travel longitudinally across said inclined tracker-bar in a direction from one side toward the other side of the instrument while the music sheet is substantially inclined in a direction transversely thereof and with the margin of the music sheet having the indicia thereon located toward the lower edge of the sheet so that said indicia will be nearest to the performer.

10. In an automatic musical instrument for playing a laterally traveling music sheet, the combination of a tracker-bar inclined longitudinally in a direction forwardly and downwardly relatively to the front of the instrument, means for operatively supporting a music sheet to travel endwise across said inclined tracker-bar and in a direction from one side toward the other side of the instrument while said sheet lies in a correspondingly inclined position, and automatic playing means to cooperate with the music sheet to play it.

11. In an automatic musical instrument adapted to play a music sheet having perforations, the combination of means for operatively supporting said music sheet to travel endwise in a direction from one side toward the other side of the instrument, including a driving roll, and means to revolve said roll situated at the top of said sheet.

12. In an automatic musical instrument adapted to play a music sheet having perforations, the combination of means for operatively supporting said music sheet to travel endwise in a direction from one side toward the other side of the instrument, in-

- cluding a driving roll, and means to revolve said roll situated at the top of said sheet, and a tracker bar extending crosswise of the direction of travel of the sheet.
- 5 13. In an automatic musical instrument adapted to play a music sheet having perforations, the combination of a tracker box, rolls mounted in such box in position to support the sheet for travel endwise in a direction from one side toward the other side of the instrument, and roll-rotating means mounted at the top of said box.
- 10 14. In an automatic musical instrument adapted to play a music sheet having perforations, the combination of a tracker box, rolls mounted in such box in position to support the sheet for travel endwise in a direction from one side toward the other side of the instrument, and roll-rotating means
- 15 20 mounted at the top of said box, said box being movably supported so that the angle at which it stands may be varied.
- 16 15. In an automatic musical instrument, a tracker bar substantially inclined downwardly and forwardly relatively to the front 25 of the instrument, a musical sheet having note perforations in the body thereof, and words of a song at the lower marginal portion of the music sheet which is nearest to the performer, and means for operatively 30 supporting said music sheet to travel longitudinally and horizontally across said inclined tracker bar while the music sheet is substantially inclined in a direction transversely of its length with such words located 35 at the forward lower marginal portion of the music sheet.

In testimony that I claim the foregoing I have hereunto set my hand.

THOMAS McKEE.
